UNITED STATES PATENT OFFICE.

ALEXANDER VEITCH, OF CANTON, NEW YORK.

GAGE AND MARKING DEVICE.

No. 927,903.

Specification of Letters Patent.

Patented July 13, 1909.

Application filed September 21, 1908. Serial No. 453,905.

To all whom it may concern:

Be it known that I, ALEXANDER VEITCH, citizen of the United States, and a resident of Canton, in the county of St. Lawrence and State of New York, have invented a new and Improved Gage and Marking Device, of which the following is a full, clear, and exact description.

This invention relates to a class of gages employed by woodworkers for marking the outlines of mortises or open recesses in case-
10 ment-jambs and door stiles, to receive hinges; and the purpose of my invention is to provide novel details of construction for a device of
15 the character indicated, which is especially well adapted for the purpose specified, and which also may be used as a depthening and outlining gage for forming recesses in other constructions of wood or metal.

20 The invention consists in the novel construction and combination of parts, as is hereinafter described and defined in the appended claims.

Reference is to be had to the accompanying drawings forming a part of this specification, in which similar characters of reference indicate corresponding parts in all the views.

Figure 1 is a plan view of the improved gage and marker; Fig. 2 is an edge view of the
30 same, seen in direction of the arrow x in Fig. 1; Fig. 3 is a reversed plan view of the gage and marker; Fig. 4 is a longitudinal sectional view, substantially on the line 4—4 in Fig. 1; Fig. 5 is a reversed plan view of a T-head that
35 is a detail of the invention, seen in direction of the arrow x' in Fig. 2, and Fig. 6 is a detached plan view of an adjustable gage-block, seen in direction of the arrow x^2 in Fig. 4.

The body portion 10 of the improved tool
40 is formed of metal, and comprises a flat slab-like block of suitable thickness, and having a rectangular marginal shape. At the transverse center and at a nearly equal distance from the ends thereof, a slot a is formed in the body 10, having a considerable length.

A slideable gage-block 11 is a novel detail, and, as is best shown in Figs. 3 and 4, consists of a rectangular block of metal, having suitable width and thickness and a length
50 equal to the width of the body 10. At the center of the gage-block a tongue 11^a is formed or secured thereon, consisting of a metal strip having parallel sides and a width that adapts it to fit neatly in the slot a . A
55 clamping-screw 12, having a collar 12^a there-

on that is integral with the knurled head 12^b of the screw, is screwed through a threaded perforation in the center of the gage-block 11, after the tongue 11^a is inserted into the slot a from the normally lower side of said block.

It will be noted in Fig. 3, where the collar 12^a of the set-screw 12 appears in dotted lines, that the diameter of said collar is greater than the width of the slot a , and that opposite portions of the collar have contact with the upper surface of the gage-block 11 near the slot, which adapts the set screw to clamp the head-block at any point of longitudinal adjustment for said gage-block in the slot, and hold it secured. Furthermore, as the block 11 is projected from the lower surface of the body 10, its transverse disposal thereon adapts said block to serve as an abutment for gage-markers that will be described.

Upon one end of the body block 10, as shown in Figs. 3 and 4 at the left, a short scribing-blade b is formed or secured at the transverse center thereof, and it will be apparent that this blade, in conjunction with the gage-block 11, affords means for scribing score-lines in wood, parallel with a true shoulder on the wooden material, against which the true transverse edge of the gage-block 11 is reciprocated, while pressure is applied upon the body 10 over the blade b .

It will be noted that the scribing-gage just described affords means for scribing score-lines on the flat surface of a door or case-
90 ment-jamb, while the block 11 is held against and slid upon an edge or shoulder of the material at right angles to said surface.

To enable the scoring of a line parallel with a surface and at a desired depth, in a surface at a right angle thereto, means have been provided that appear at the right-hand end of the body 10, in Figs. 1 to 4 inclusive, comprising the following details: A gage-screw 13, having an elongated body 100 and a knurled head 13^a, is screwed into a threaded perforation in the body 10 near the right-hand end thereof, and preferably at its transverse center. Upon the gage-screw 13 a sleeve-nut 13^b is mounted before the engagement of the gage screw with the body 10 and as shown, said nut is roughened peripherally to facilitate its manual adjustment. A scribe-head c is secured on the threaded end of the gage-screw 13, after it 105
110

has been screwed into the body 10, preferably by means of a clamping screw c' , and upon the lower end of said scribe-head a circular blade or V-shaped rib d is formed, 5 as is clearly shown in Figs. 3 and 4. It will be seen that the sleeve-nut 13^b serves as a jam-nut for securing the scribe-head c projecting below the lower surface of the body 10, any distance that the length of the gage 10 screw 13 permits, so that a sliding movement of the body 10 over a flat surface, such as the stile of a door or a casement-jamb, with the gage-block 11 in contact with said surface, will permit a score-line to be formed 15 at a desired depth from the surface whereon the body 10 is slid in the edge of a door or a door-jamb, as the case may be.

The scribing means just described, is designed to facilitate the formation of depth 20 lines for the embedment of large hinges having thick leaves, in the edge and jambs of heavy doors and their casements, and also for laying out mortises in doors or other woodwork.

25 For forming score-lines on doors and door-casements of ordinary thickness, a supplementary scribing means is provided, which is shown at the left in Figs. 1 to 4 inclusive, in the drawings. Two parallel guides 14 are 30 formed on the upper surface of the gage-body 10 and receive between them a member of a T-shaped head-piece 15, having a transverse bar 15^a formed thereon at right angles thereto. In the T-head member 15 a longitudinal slot 35 d' is formed, through which passes the screw-threaded body 16^a of a clamping-screw, the head portion 16 of which is circular, is peripherally roughened, and has such a diameter as permits it to overlap the defining side edges of the slot d' when the screw 40 engages a tapped hole d^b in the body 10, said hole being formed interiorly for the reception of said screw. The transverse head portion or member 15^a of the T-head has parallel 45 sides and projects below the member 15, so as to provide a shoulder e, that is at right angles with the side edges of the tongue member 15, and parallel with the end wall e' of the gage body 10. Centrally on the lower 50 outer corner of the transverse member 15^a a small scribing blade g is formed or secured, which will produce a scored line or indentation in wooden material, such as a door, along its edge that is to receive the leaf of a 55 hinge. In this scribing device the end wall e' of the body 10 that is nearest to the T-member 15^a, becomes the shoulder that engages the surface of a door-stile, and the scribe-blade g marks the depth line for a recess that 60 is to receive the leaf of a hinge, and it will be seen that by an adjustment of the T-head member 15 the depth-line may be positioned at exactly the correct depth, and to facilitate such an adjustment, a scale graduation h is 65 produced on the upper surface of one of the

guides 14, on which a corner of the member 15 will register and indicate the proper depth for a recess.

It will be seen that the supplementary gage is available for marking the scores which 70 determine the depth of a recess for the reception of a hinge leaf, and also the width thereof from the pintle-sleeve to the edge of the leaf that is opposite from said sleeve, if the hinges are of ordinary size. 75

As an adjustment of the gage-block 11 so as to locate it at either end of the slot a, will locate it at some distance from the end of the gage body that is nearest to the opposite end of the slot a, it will be seen that the gage 80 block 11 and the side edges of the body 10 will serve as a T-square for use in marking the score-lines at the ends of the recesses for the hinges.

It is obvious that the improvement may be 85 given dimensions that best suit its service, and that the tool complete may be made of steel or other available metal.

Having thus described my invention, I claim as new and desire to secure by Letters 90 Patent:

1. A gage and marker, comprising a flat body portion having a longitudinal slot between its ends, and a depending scoring-blade at one end thereof, a gage block having 95 parallel sides and corresponding in length to the width of said body, the said gage block engaging the unders face of said body portion, a rectangular tongue on the upper face of said gage block at the center thereof and extending at right angles thereto, said tongue being slidably adjustable in said slot, and a set screw screwing in a threaded perforation in the said tongue and gage block, the said screw having a head, and an integral collar 100 of greater diameter than the width of the said slot and bearing on the upper surface of said body portion at opposite sides of the slot.

2. The combination with a rectangular 110 flat body-block having a central, longitudinal slot therein, a gage-block having a tongue that slidably engages the slot, and a clamping screw for securing the gage-block at a selected point on the block-body, of a scoring 115 means embodying a threaded bolt screwed through the body-block, near one end thereof, a jam-nut adjustable thereon, and a scoring block having a circular scoring edge and removably secured on the threaded end 120 of the bolt.

3. The combination with a rectangular flat body block, and a gage-block securable transversely thereon, of a scoring means, comprising a threaded bolt having a roughened head, an adjustable jam-nut thereon, the threaded end of the bolt screwing through a tapped perforation in the body-block, a circular-bodied scoring block removably secured on said end of the bolt, and a 130

circular V-shaped scoring rib projected from the lower end of the scoring-block.

4. In a gage and marker, a flat body portion having a longitudinal slot between its ends, and a depending scoring-blade at one end thereof, a gage block having parallel sides and corresponding in length to the width of said body, the said gage block engaging the under face of said body portion, a rectangular tongue on the gage block at the center thereof and extending at right angles thereto, the said tongue being adjustable in said slot, and means for clamping said gage block and tongue at a desired point.
5. In a gage and marker, the combination with a flat body block having a longitudinal slot therein, a gage block engaging the slot, and means for clamping the gage block at a desired point, of a threaded bolt screwed through the body block, near one end thereof, a nut adjustable on said threaded bolt, and scoring means carried at the end of the bolt.
6. In a gage and marker, the combination

with a flat rectangular body having two parallel guide-ribs formed on its upper surface at one end, of a T-shaped head piece comprising a longitudinally slotted member having parallel sides and fitting between the guide ribs, and a transverse member at the outer end of said slotted member, the said transverse member projecting below the slotted member forming a shoulder extending at right angles to the side edges of the slotted member, and parallel with the adjacent end wall of the body block, a depending scoring blade on the lower surface of said transverse member at the outer edge, and means for clamping the said head piece in position on the body block.

In testimony whereof I have signed my name to this specification in the presence of two subscribing witnesses.

ALEXANDER VEITCH.
